D. G. SCHUCKER.
ATTACHMENT FOR BED SPRINGS.
APPLICATION FILED MAR. 11, 1915.

Patented Feb. 8, 1916.

FIG. I.

FIG. II.

UNITED STATES PATENT OFFICE.

DANIEL G. SCHUCKER, OF SELINSGROVE, PENNSYLVANIA.

ATTACHMENT FOR BED-SPRINGS.

1,170,852.

Specification of Letters Patent.

Patented Feb. 8, 1916.

Application filed March 11, 1915. Serial No. 13,627.

To all whom it may concern:

Be it known that I, DANIEL G. SCHUCKER, a citizen of the United States, residing at Selinsgrove, in the county of Snyder, State of Pennsylvania, have invented certain new and useful Improvements in Attachments for Bed-Springs; and I do hereby declare the following to be a full, clear, and exact description of the invention, such as will enable others skilled in the art to which it appertains to make and use the same.

This invention relates to attachment for bed springs.

The object of the invention resides in the provision of an attachment for bed springs through the instrumentality of which a bed spring may be associated with either a metal bed or a wood bed.

A further object of the invention resides in the provision of an attachment of the type named which will be simple in construction, easily adjusted, and readily associated with a metal frame bed spring of ordinary construction.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a perspective view of one corner of a metal frame bed spring having the attachment associated therewith and showing the spring applied to a metal bed, the latter being disclosed in dotted lines, and Fig. 2, a perspective view of one corner of a metal frame bed spring having the attachment associated therewith and showing the spring applied to a wood bed, the latter being disclosed in dotted lines.

Referring to the drawings A indicates generally a metal frame bed spring. One of the end members of the spring A is shown and indicated at 10 and depending from the end member 10 is an angle iron arm 11 connected at its lower end to the tubular supporting rail 12 all as is well known in the construction of metal frame bed springs.

The attachment is shown as comprising a sleeve 13 slidable on the rail 12 and carrying a set screw 14 for securing the sleeve against sliding movement on the rail as will be obvious. The end of the sleeve 13 adjacent the arm 11 is provided with diametrically opposite corresponding recesses 15 corresponding in shape to the cross section of the arm 11 and adapted to receive the latter when the sleeve is moved to its limit toward the arm 11 and whereby said sleeve is secured against rotation on the rail 12 through the medium of the interlocking engagement between the arm and sleeve thus established. The sleeve 13 has formed integral therewith a lateral wing 16 which is adapted to support the spring when the latter is applied to a metal bed.

It will of course be understood that two attachments are applied to each supporting rail of the spring and when the latter is applied to a metal bed the attachments are adjusted in interlocking relation with respective arms 11 with the wings 16 disposed outwardly and in position to engage the side rails of the bed, such side rail being indicated at 18 in Fig. 1.

If it is desired to apply the spring A to a wood bed the attachments are adjusted in interlocking relation with the arms 11 with the wings 16 disposed inwardly when the rails 12 will directly engage slats 19 and support the springs.

What is claimed is:—

An attachment for bed springs comprising a sleeve adapted to be slidably and rotatably mounted on the side rail of a bed spring and having diametrically opposite corresponding recesses in one end one of which is adapted to receive the corner arm of a bed spring when the sleeve is moved to its limit in one direction on the side rail of the bed spring, and a lateral wing carried by said sleeve for engaging the side rail of a bed when said sleeve is rotated to dispose the wing outwardly with respect to the spring.

In testimony whereof, I affix my signature, in the presence of two witnesses.

DANIEL G. SCHUCKER.

Witnesses:

GEO. S. SCHOCH,
S. R. MICHAELS.
